ARTICLE CONTAINING AND DISPENSING DEVICE

Otto Fischer, Vienna, Austria, and Max E. Bernhardt, New York, N. Y.; said Fischer as signor to said Bernhardt

Application November 2, 1933, Serial No. 696,340

11 Claims. (CI. 206—41)

This invention relates to dispensing containers and while not restricted to such use, it is particularly designed as a container or case for cigarettes and includes means which upon each actuation thereof partially ejects a cigarette so as to facilitate the grasping and manual removal of the same from the case.

The invention broadly resides in a cigarette case having means for partially ejecting the cigarettes through an opening in the case together with means for feeding a cigarette into a position in alignment with the said opening each time a cigarette is removed from the case.

The invention more specifically resides in a cigarette case which includes separable sections which are movable relatively to each other, in order to gain access to the interior thereof for the purpose of filling or charging the case with cigarettes, and which sections are provided with interengageable means functioning upon relative movement of said sections to eject a portion of one end of a cigarette from the case through a dispensing opening in the side wall thereof each time the sections are moved from a fully closed position towards its open position.

The invention further embodies a cigarette case in which, if desired, the body and cover sections may each be completely cut, bent and formed from a single blank of stock so as to provide interfitting unitary structures.

Other objects which fall within the purview of the invention are to provide a cigarette case of the character indicated which is comparatively simple and not unduly complicated in its construction, admitting of economical production thereof and which is highly efficient for its intended purpose.

With the above recited and other objects in view, reference is made to the following specification and accompanying drawings in which there is illustrated, by way of example, two embodiments of the invention, while the appended claims are intended to cover other forms thereof which fall within their scope.

In the drawings, illustrating the invention, Fig. 1 is a front view of a cigarette case constructed in accordance with the invention and illustrating in dotted lines the ejector in retracted tensioned position.

Fig. 2 is a view partially in section illustrating the means for advancing the cigarette supply to dispose the leading cigarette in a position to be ejected by the next actuation of the ejecting means, and showing the case sections in relative

position wherein the ejecting means has effected the partial ejection of a cigarette.

Fig. 3 is a plan view illustrating the case sections in opened relation for filling the case.

Fig. 4 is a longitudinal cross sectional view taken on the line 4—4 of Fig. 3.

Fig. 5 is a similar sectional view taken on the line 5—5 of Fig. 3.

Fig. 6 is a perspective view of the container body section.

Fig. 7 is a perspective view of the cover section.

Fig. 8 is a perspective view of the spring actuated follower member for moving the cigarettes into dispensing position.

Fig. 9 is a perspective view of another form of cigarette case with the sections in open relation.

Fig. 10 is a rear view of the case illustrated in Fig. 9, the same being shown on a reduced scale.

Referring to the drawings by characters of reference, the cigarette case includes a container body section A and a cover section B which are slidably associated for relative movement from a closed to an opened relation for filling and for relative movement to effect the partial ejection

of a portion of the end of a cigarette during each dispensing operation. As shown, the container body section A is substantially rectangular shaped in cross section and includes a rear wall 10 which has joined thereto along its side edges and at its ends respectively, upstanding side walls 11 and 12 and forwardly curved arcuate end walls 13 and 14 which end walls carry front wall portions 15 and 16 directed inwardly toward each other and spaced from each other and the rear wall 10.

The end wall 13 and the front wall portion 15 have their undersurfaces adjacent their side edges in engagement with the edges of the side walls 11 and 12. The side wall 11, at the opposite end of the section, is reduced in length and has a concave arcuate end edge 18 which is spaced from the end wall 14 to define together with said wall 14 a dispensing opening 19, through which the cigarettes are ejected, and dispensed. Adjacent the

said opening, the upper edge of the side wall 11 is engaged by the undersurface of the front wall portion 16.

The wall 12 has its front edge offset inwardly from a point adjacent the innermost edge 20 of the top wall portion 15 and extending to the arcuate convex edge 21 thereof, which edge 21 contacts with the undersurface of the end wall 14.

Carried by and extending inwardly from the offset portion of the front edge of the side wall 12 is a front wall portion 22, the inner edge 23 of

which portion 22, together with the inner edge 20 of the front wall portion 15 and the inner edge 24 of the front wall portion 16 and the front edge 25 of the side wall 11 defines a rectangular shaped opening 26 for gaining access to the interior of the body section A to introduce the cigarettes for filling or charging the case.

The front wall portion 16 is provided with an elongated recess 27 opening through the edge 24 and extending inwardly therefrom and dividing the said wall portion 16 into opposite side areas 28 and 29, the side area 29 overlying one end of the front wall portion 22 and being held in spaced relation thereto by means of a tongue 30 struck up from the wall portion 22. The spaced wall portions 22 and 29 afford a clearance for and between which an ejector arm 31 is movable to and from its retracted tensioned position. The ejector arm 31 is anchored at one end as at 32 to the upper surface of the front wall portion 22 and has its free offset end fashioned to provide a cigarette engaging terminal 33 disposed in alignment with the dispensing opening 19 for contacting with and moving the outermost cigarette of the supply laterally of its case and to partially project through the dispensing opening.

Adjacent the terminal 33 the ejector arm 31 is laterally bent to provide an angularly disposed cam portion 34 and a straight portion 35, the cam portion 34 being engaged by a depending flange 36 of a plate 37. The plate 37 is also provided with an inwardly projecting stop lug 38 which is adapted to contact with a stop finger 39 formed at the edge 23 of the front wall portion 22 so as to normally limit the relatively sliding movement of the case sections A and B the required distance to actuate the ejector means.

In order to provide means whereby the stop lug 38 may be disposed out of the path of the stop finger 39 to permit the opening of the case sections, the plate 37 is fulcrumed to the underside of the cover section B on a pivot 40 with a slot 41 being provided in said section in which a pin 42 moves so as to guide and limit the swinging of the plate. This arrangement permits of the grasping of the head of the pin 42 for manually swinging the plate to allow the stop lug 38 to pass the stop finger 39. The plate 37 is returned to normal position upon the subsequent actuation of the cigarette dispensing device as the flange 36 engages with the ejector arm 31.

The ejector arm 31 is inherently resilient and is so disposed upon the front wall portion 22 that when the cover section B is moved to closed position, from the position in which the stop lug 38 of the plate 37 is against the stop finger 39, the flange 36 of the plate 37 slides over the cam portion 34 of the ejector arm and swings the free end of the arm laterally into retracted tensioned position for engagement behind the outermost cigarette. When in this position, the flange 36 of the plate 37 is in contact with the straight portion 35 of the ejector arm, which flange holds the ejector arm in tensioned position until released by the retraction of the cover section B from fully closed position, in order to effect the ejection of an end portion of the endmost cigarette whereby to facilitate the grasping and complete removal thereof, a lug 53 limiting the movement of the ejector arm 31.

The container section A may be of a size to receive and accommodate any desired number of cigarettes which are transversely disposed in contiguous parallel relation in a single row and between the end wall 14 and a spring actuated

follower 43 which follower functions to successively move the cigarettes into position for removal where the terminal element 33 of the ejector arm 31 lies behind the innermost end of the cigarette to be engaged and axially moved thereby to the partially ejected position illustrated in Figs. 2 and 3.

The follower 43 includes a wall 44 having a concave leading face within which is received the innermost cigarette of the supply and which wall has joined thereto, marginal rearwardly directed side walls 45 and end walls 46. The follower 43 is urged toward the end wall 14 of the container body section A by an accordion folded spring 47, the upper end of which spring is disposed against the underside of the arcuate wall 44 and lies between the side and end walls 45 and 46, the opposite end of said spring abutting against the end wall 13 of the said section. One of the side walls 45 of the follower 43 carries a latch plate 48 which is provided with a rearwardly projecting upwardly offset portion 49 cut out as at 50 and forming a detent tongue 51 which is adapted to engage with an inwardly pressed keeper lip 52 formed by slitting the front wall portion 15 and serving to temporarily hold the follower in retracted position while filling the container with cigarettes. The detent is released from the keeper by manually lifting the forwardly extending extremity 54 of the front wall portion 15 which raises the keeper lip 52 out of engagement with the detent tongue 51.

The cover section B is provided with a front wall 55 which wall overlies and forms a closure for the opening 26 in the container body section A, the said front wall 55 being provided with marginal side walls 56 and 57 which walls are provided with inwardly directed flanges 58 which engage with the rear wall 10 of the body section A to afford a slidably guided connection between the sections A and B.

The ends of the side wall 56 of the cover section B extend beyond the top and bottom edges of the front wall 55 thereof and have convex arcuate end edges 59 and 60 which conform to the curvature of the end walls 13 and 14 respectively. The side wall 57 of the cover section B has its lower end projecting beyond the bottom edge of the front wall 55 and has its end edge 61 similarly convexly curved, the opposite end of the side wall 57 being reduced in length and having a concave arcuate end edge 62 which edge abuts against an outwardly pressed inwardly recessed portion 75 of the side wall 12 which portion forms a stop boss to limit the sliding movement of the cover section B upon the body section A and provides a pocket for the terminal end 33 of the ejector arm 31 so that the same is disposed when in retracted tensioned position flush with the inner face of the side wall 12 and out of the path of the inner end of the cigarettes as they are shifted into position to be dispensed.

The spring 47 has its terminal 72 downwardly inclined between the topmost convolutions 73 and 74 thereof and in contact with the convolution 73 so as to dispose the central portion of the topmost convolution 74 in balanced engagement with the central portion of the wall 44 of the follower 43 so that the follower 43 is moved evenly by the spring 47 and without canting thereof.

It will be observed that when the cover section B is arranged in fully closed relation upon the container section A, the plate 37 is disposed in the recess 27 with the flange 36 thereof positioned against the straight portion 35 of the ejector

arm 31 and with the arm 31 in retracted tensioned position. When the cover section B is moved to fully opened position on the container section A, for filling the container section, the stop lug 58 abuts against the inner edge of a recess 63 opening through the edge 20 of the front wall portion 15 and extending inwardly therefrom adjacent the extremity 54 thereof. The side area 28 of the front wall portion 16 is provided with a recess 64 extending inwardly from the edge 24 thereof which forms an opening for the thumb by which the latch plate 48 may be engaged and manually retracted into latched engagement with the keeper lip 52 for filling the container section A.

In the embodiment illustrated in Figures 9 and 10, the construction closely follows the previously described form but in this instance, the container section is provided with an elongated slot 65 in the bottom wall 10a, which slot has a laterally extending notch 66 at its lower end and a similar laterally extending notch 67 intermediate its ends for guidedly receiving the pin 68 carried by the bottom wall 45a of the follower 43a. The pin 68 is provided with enlarged heads 69 and 70 and is slidable in a laterally extending slot 71 in the bottom wall 45a of the follower 43a by means of which the pin 68 may be disposed in either one of the notches 66 or 67 for temporarily latching the follower 43a in either of two positions for filling the container section.

What is claimed is:

1. In a cigarette dispensing container, a pair of interengageable slidably movable sections providing an interior chamber for holding a supply of cigarettes to be dispensed, one of said sections having a dispensing opening and a resilient ejector means functioning upon relative sliding movement of said sections to effect a partial ejection of a cigarette through said opening upon each operation of said means.

2. In a cigarette dispensing container, a pair of interengageable slidably movable sections providing an interior chamber for holding a supply of cigarettes to be dispensed, one of said sections having a dispensing opening, swinging means functioning upon relative sliding movement of said sections to effect a partial ejection of a cigarette through said opening upon each operation of said means and means for successively moving the cigarettes contained in said chamber to dispose the endmost cigarette in a position to be acted upon by the ejecting means.

3. In a cigarette dispensing container, a hollow body section having an opening for filling the section, a cover section, said cover section being slidable upon and relative to the hollow body section to gain access to the interior of the hollow body section through said opening, said body section having a dispensing opening, and a resilient ejector element anchored at one end to said hollow body section and having a free end disposed in alignment with said discharge opening when in retracted position and functioning upon relative sliding movement of said sections to effect a partial ejection of a cigarette through said dispensing opening.

4. In a cigarette dispensing container, a hollow body section having an opening for filling the section, a cover section, said cover section being slidable upon the hollow body section to gain access to the interior of the hollow body section through said opening to fill the same, said body section having a cigarette dispensing opening, tension means functioning upon relative sliding

movement of said sections to effect a partial ejection of a cigarette through said dispensing opening, and means functioning upon relative movement of said sections to move the first named means to retracted tensioned position.

5. In a cigarette dispensing container, a hollow body section providing a cigarette receiving chamber and having an opening for filling the chamber, a cover section, said cover section being so constructed and arranged as to be slidably movable upon the hollow body section to and from closed position overlying said opening, said body section having a cigarette dispensing opening, a resilient ejector element anchored at one end to the said hollow body section and having a free end disposed in alignment with said discharge opening when in retracted tensioned position and means carried by said cover section functioning by and upon relative movement of said sections to swing the ejector element from an untensioned position to retracted tensioned position and in position for partially ejecting a cigarette through said dispensing opening by retraction of the cover section.

6. In a cigarette dispensing container, a body section, said section including a bottom wall, end and side walls, a laterally disposed top wall portion connected with one of said side walls and inwardly directed top wall portions connected respectively to the end walls, the inner edges of said top wall portions, and the free edge of said other side wall defining an opening entering into a cigarette receiving chamber formed by said walls, one of said side walls having a cigarette dispensing opening, a cover section so constructed and arranged as to be slidably movable upon the body section to overlie and close the said first mentioned opening, a resilient ejector element anchored at one end upon the said lateral top wall portion and having a free end disposed in alignment with said discharge opening when in retracted tensioned position, and depending means carried by the under side of said cover section functioning by and upon relative movement of said sections to swing the ejector element from an untensioned position to retracted tensioned position and in position for partially ejecting a cigarette through said dispensing opening upon retraction of the cover section from closed relation.

7. In a cigarette dispensing container, a hollow body section providing a cigarette receiving chamber and having an opening for filling the chamber, a cover section, said cover section being so constructed and arranged as to be slidably movable upon the hollow body section to and from closed position overlying said opening, said body section having a cigarette dispensing opening, a resilient ejector element anchored at one end to the said hollow body section and having a free end disposed in alignment with said discharge opening when in retracted tensioned position, means carried by said cover section functioning by and upon relative movement of said sections to swing the ejector element from an untensioned position to retracted tensioned position and in position for partially ejecting a cigarette through said dispensing opening by retraction of the cover section, a spring actuated follower slidably movable within the hollow body section for successively moving the supply of cigarettes contained therein to dispose the endmost cigarette in a position to be acted upon by the ejector element and means for latching the said follower.

in retracted position for filling the hollow body section.

8. In a cigarette dispensing container, a body section, said section including a bottom wall, end and side walls, a laterally disposed top wall portion connected with one of said side walls and inwardly directed top wall portions connected respectively to the end walls, the inner edges of said top wall portions, and the free edge of said other side wall defining an opening entering into a cigarette receiving chamber formed by said walls, one of said side walls having a cigarette dispensing opening, a cover section so constructed and arranged as to be slidably movable upon the body section to overlie and close the said first mentioned opening, a resilient ejector element anchored at one end upon the said lateral top wall portion and having a free end disposed in alignment with said discharge opening when in retracted tensioned position, depending means carried by the under side of said cover section functioning by and upon relative movement of said sections to swing the ejector element from untensioned position to retracted tensioned position and in position for partially ejecting a cigarette through said dispensing opening upon retraction of the cover section from closed relation, and a spring actuated follower slidably movable in the said chamber for successively moving the supply of cigarettes contained therein to dispose the endmost cigarette in a position to be acted upon by the ejector element.
9. In a device of the class described, a pair of interengaging slidable movable sections, said sections each being constructed from a sheet of plain stock, one of said sheets being so cut and bent as to provide a bottom wall, a pair of upstanding side walls and outwardly curved articulate end walls to thereby form one of said sections, said walls defining a chamber for holding a supply of cigarettes and providing an opening for filling the chamber, the other of said sheets being so cut and bent as to provide a front wall and side walls joined to the marginal edges of said front wall to thereby form the other section, said front wall overlying and forming a closure for the opening in said first mentioned section and being provided with inwardly directed flanges

which engage with the bottom wall of said first mentioned section to afford a slidably guided connection between said sections, and a stop for limiting the relative sliding movement of said sections for positioning the sections in closed relation.

10. In a dispensing container for articles of the character set forth, a pair of interengaging relatively movable mating sections, said sections providing an interior chamber for holding a supply of articles to be dispensed, one of said sections having a dispensing opening, an article ejecting means so constructed, arranged and actuated by one of said sections upon relative movement of the sections as to effect a partial ejection of an article through said opening upon each operation of said means, a spring actuated follower slidably movable within said chamber for successively moving the supply of articles contained therein to dispose the endmost article in a position to be acted upon by the ejecting means, and interengaging latch and keeper means carried by said follower and one of said sections respectively for latching the follower in retracted position for filling the chamber.

11. In a dispensing container for articles of the character set forth, a pair of interengaging relatively movable mating sections, said sections providing an interior chamber for holding a supply of articles to be dispensed, one of said sections having a dispensing opening, an article ejecting means so constructed, arranged and actuated by one of said sections upon relative movement of the sections as to effect a partial ejection of an article through said opening upon each operation of said means, a spring actuated follower slidably movable within said chamber for successively moving the supply of articles contained therein to dispose the endmost article in a position to be acted upon by the ejecting means, one of said sections having an elongated notched slot opening into the chamber and means movably carried by said follower and movable into engagement with the notch of said slot for temporarily latching the follower in retracted position for filling the chamber.

OTTO FISCHER.
MAX E. BERNHARDT.
